UNITED STATES PATENT OFFICE.

HERMAN L. STRONGSON, OF NEW YORK, N. Y.

SHADE STOP.

Application filed September 14, 1927. Serial No. 219,498.

This invention relates to shade roller fixtures for use in connection with window shades of all kinds and has several objects in view as will be explained.

5 A main object of this invention is to provide means to stop the rotation of the shade roller when the lower end of the shade reaches a position proximate the roller to prevent the shade from flopping, beating and 10 unrolling when it is accidentally released from one's hand.

Another object is to provide various modifications of the shade roller fixture wherein the invention is made useful on all forms of 15 windows and shade roller construction.

A further object is to provide a fixture which includes stop means to engage a shade stick or the like intermediate its end so as to avoid throwing all the strain on the shade 20 near its outer edges. In this way the shade roller is restrained against the usual unrolling action by gripping the shade stick along its entire length, which is to say that the sudden strain and force, incident to stopping 25 a rapidly running shade, is applied throughout the width of the shade thereby avoiding damage to the shade which would result if the strain were thrown merely on its edges.

Further objects of the invention are to 30 make the fixture adjustable in length by which it is fitted to any width window and hence to any length shade roller, and to make a fixture which is easily attached to the roller, and which does not necessarily require 35 nails or screws by which it is installed on the window casing, and to provide means by which the device is held or locked against rotation to prevent it from being displaced about the axis of the shade roller when the 40 rapidly running shade is suddenly stopped.

The accompanying drawings show several examples of the invention which are capable of being altered in various particulars, and wherein,

45 Figures 1 through 7 show the first form of the invention. Figure 1 is a front view of a window casing and shade, and more particularly showing a shade roller fixture mounted on the shade roller. Figure 2 is 50 an end view of the shade roller with the fixture mounted thereon and removed from the window to afford an unobstructed view of that end of the shade roller which is ordinarily provided with a round shaft or trunnion. Figure 3 is a view showing the other

end of the shade roller, being the square shaft end, with the fixture in place. Figure 4 shows a cross section on the line 4—4 of Figure 1 which illustrates the manner of gripping the tapered shade stick between the 60 spaced stop members. Figure 5 is a plan view of the fixture removed from the shade and Figure 6 is a longitudinal section side view through one of the telescoping shade stick guide and stop members. Figure 7 shows the 65 pair of support or swing arms which carry the shade stop means.

Figures 8 and 9 show a second form of the invention for new house work wherein the shade roller bracket is made to also carry the 70 stop means to reduce the number of parts. Figure 8 is a front view of the shade roller carried by the novel bracket and the view also shows the brackets extended downwardly to carry novel shade stick stop means. Figure 75 9 is a bottom plan view of the fixture shown in Figure 8 but with the shade removed.

Figures 10 and 11 show a third form of the shade roller fixture, Figure 10 being a perspective view of the fixture made from two 80 pieces of flat telescoping tubes, and Figure 11 is a cross section.

Figures 12 through 14 illustrate a fourth form of the invention wherein another novel locking means prevents displacement of the 85 fixture, Figure 12 being an enlarged view of one end of the shade roller with which the modified fixture is attached, and a locking ear engages the shade roller bracket. Figure 13 shows a sectional view taken on the line 90 13—13 of Figure 12. Figure 14 is a perspective view of one of the novel arms which carry the shade guide stop, showing the locking ear. This view also shows a slot leading to the shade roller shaft bearing by which the 95 fixture is installed without removing the shade roller.

In accordance with the principles of this invention, I construct a shade guide and roller stop by providing support means mounted 100 concentric in respect to the shade roller axis and said means is suspended beneath the shade and is so constructed that it leaves the entire shade free and exposed to view. The support means carries a stop against which 105 the shade stick or equivalent means comes to rest when the shade flies up and the roller is therefore prevented from unwinding, an important feature being that the stop may engage the shade across the entire width of the 110

latter so as to distribute the sudden strain incident to stopping the shade when it reaches the end of its run.

Referring further to the drawings for a more detailed description of several examples of the invention, and describing the first form, there is shown an ordinary shade roller R on which the shade S is rolled in the usual way, and the shade S may be provided with a conventional pull cord P. Ordinary shade roller support brackets B are anchored to the window case and in which the square shaft SQ of the shade roller is mounted as well as the round shaft RS at the other end of the shade roller which is a well known construction. A shade stick ST or other lower shade end means is carried on the free end of the shade S. The shade roller R is driven by an inside concealed spring, as every one knows, adapted to wind up the shade, and it is well known that the shade frequently gets out of control because the pull P or stick S becomes released from one's hand with the result that the shade beats about the window casing so it must then be taken down and the spring rewound and remounted, all of which leads to inconvenience and wear and tear on the shade.

In general this invention affords means for engaging and stopping the shade stick ST along its full length or at its center so as to afford a positive stop without tearing or damaging the shade when the pull P is released from one's hands. To this end, support means in the form of depending arms 12 and 13 are provided with bearing apertures 14 and 15. The bearing apertures are mounted on the respective round shaft RS and square shaft SQ of the shade roller with a result that the two support arms 12 and 13 hang down from the shade roller shafts and are concentric therewith. The support arms may be offset at 16 so as to bring the lower end of the arms out away from the edge of the shade to afford a running and guiding clearance between the edge of the shade and fixture.

A suitable shade stick stop, such as parallel telescoping tubes, or other stop means, are carried by the arms 12 and 13 to swing concentric with and beneath the shade roller. To this end one arm 13 may have a pair of large size tubes 18 anchored therein. The other arm 12 has small tubes 19 anchored thereto. The parallel spaced tubes 18 and 19 are telescoped one in the other with a result that the support arms 12 and 13 are in fact carried on the ends of the telescoping tubes. In this way the arms 12 and 13 are adjustable apart and may be brought closer or further away from one another to accommodate any width shade and any length roller. For a long roller, the telescoping tubes 18 and 19 are pulled outwardly and for a short roller the shade tubes are slid together inwardly, the

object being to so place the bearing apertures 14 and 15 upon the square and round roller shafts at each end of the shade roller R that the shade stick stop 18-19 swings freely beneath the roller with the shade cloth S placed therebetween.

The shade cloth S is operatively placed between the telescoping tubes 18 and 19 in any convenient manner. For example the shade stick ST may be removed from the shade, 75 whereupon the shade is readily threaded through the two spaced telescoping tubes, and then the stick is replaced. On the other hand, the telescoping tubes may be pulled apart one from the other and replaced by assembling 80 the fixture from each edge of the shade as the arms 12 and 13 are placed on the shafts at each end of the roller, this latter method rendering unnecessary the removal of the shade stick.

The shade roller stop members 18 and 19 may be spaced apart just far enough to admit the thin edge of the shade stick but prevent the lower thick edge thereof from being jerked through the telescoping tubes when 90 the shade flies up. In this way the thin edge of the shade stick enters the space in the shade stop 18-19 and wedges thereinbetween with the result that the strain is evenly applied along the full length of the stick and 95 shade which avoids undue strain at any one point.

The first form of the device is a simple fixture which is readily attached to shades already in use, but I will now describe one for 100 new house work wherein is combined a new form of bracket with the shade guide stop means.

In Figures 8 and 9 there is shown a second form of the invention which is modified in 105 two improved respects. The shade bracket which itself supports the roller is improved in a way to make it carry the telescoping tubes or other stop means for engagement with the window shade stick; and the position of the 110 telescoping tubes is improved by mounting a small and large tube carried on each bracket so that this tube arrangement is a staggered one thereby affording a space of uniform width between the tubes for the full length 115 thereof as will now be described.

In connection with this modification, (Figures 8 and 9) a shade roller bracket 22 is provided with screw or nail holes by which the bracket can be anchored to the wall of the 120 building in the usual way. The lower end of each bracket 22 is extended to provide an arm 23 which supports the shade stick stop means. This construction affords a one piece bracket and arm by which both the roller and shade guide stop device are carried by a one piece member thus simplifying the construction. It is used in new work where a shade is first installed as in new building.

The arrangement of the parallel spaced 130

telescoping tubes in Figure 8 is also somewhat different from the former views in that a large tube 24 and a small tube 25 have their ends anchored to the lower end 23 of each bracket. In this way the telescoped stop guides are arranged in offset or staggered relation in that each arm 23 is made to carry a small tube and a large tube so that when these units are placed together, the construction will be as shown in Figure 9 which constitutes one preferred arrangement for either type of bracket, the old one B, the new one 22, or any other bracket. This arrangement equally balances the weight of the fixture and more particularly places a large and small tube at each end thereby better accommodating the shade stick therebetween, the result of which is to provide a construction which more evenly and uniformly engages the shade stick throughout its length.

Referring now to a third form of the construction as shown in Figures 10 and 11, oval or flat telescoping tubes 30 and 31 are slidable one in the other. The outer end of each tube is flattened and bent to form parallel suspension arms 32. The upper ends of the arms are provided with square perforations 33 to receive the shafts or trunnions of the shade roller. Both ends of this shade guide stop may be punched with a square hole 33 so that the ends of the fixture are interchangeable and is readily placed in position on the shade roller regardless of which ends of a roller or fixture are brought together. This guide and stop 30-31 is provided with a lengthwise slot 34 through which the shade freely runs. The width of the slot 34 is just sufficient to engage a shade stick or any other enlargement carried on the lower end of a shade.

Coming now to the fourth form of the invention shown in Figures 12 through 14, there is illustrated an arm 40 suspended by a bearing aperture 44 from the square shaft SQ of the shade roller R and the shade S is shown depending from the roller. The upper end of this arm is made with an outturned ear 41 which rests within and engages the shade bracket slot SB which receives the square shaft end of any roller. By making the ear 41 slightly narrower than the width of the slot SB, it follows that the lower end of the arm 40 is capable of a limited rocking or pivotal motion beneath the shade roller. This motion is limited by reason of the ear 41 resting within the slot SB of the bracket and for that reason the arm 40 is locked against rotation about the shaft roller R, and therefore the force of a shade stick coming to a sudden stop will not swing the arm 40 out of normal vertical position.

There is provided any suitable form of shade engaging stop or guiding means on the lower end of the arm or arms 40. For example there is shown the parallel telescoping tubes or rods 43 between which the shade free-

ly runs and against which the shade stick or other enlargement is adapted to engage and thereby stop and prevent the unrolling of the shade roller.

As shown in Figure 14, I may in some cases provide a slot 45 which extends into the bearing aperture 44. This slot is sufficiently wide to permit the arm 40 to be mounted in service position on the shafts of the shade roller. By tilting the arm 40 at an angle until the slot 45 passes over the shade roller shafts, the latter are received into the bearing 44. In this way, the fixture may be mounted on the shade roller without removing the shade from the bracket B, the arms 40 being made of thin stock so they may be carried on the roller shafts between the roller and the brackets secured to the building.

In the operation and use of this shade fixture, the shade is actuated in the usual way and runs between the spaced stop means of whatever character chosen, for example the parallel spaced tubes or rods. In order to run the shade all the way to the top it is only necessary to give the shade a slight pull and turn it loose whereupon it rapidly travels to the top and comes to a stop when the shade stick engages the spaced stop means as shown and described.

This invention serves to protect the shade from wear and tear since the device guides the shade in its upper travel and affords positive means to prevent the unwinding of the shade roller and the invention is presented to fill a need felt for such a device, which is now accomplished by mounting the stop means directly beneath the shade and engaging the shade stick for its full length, and also by mounting the support arm concentric with the shade. It is known that many attempts have been made to provide such improvements, but I am not aware of any fixture based on the principles of my invention and which has a like mode of operation.

The dotted line position of parts in Figure 2 shows how the shade may be pulled outwardly at any angle followed by the freely pivoted fixture. This is true of other forms of the device. Even in the form including the locking ear 41, the latter is small and loosely fits within the slot of bracket B with the result that the fixture is free to swing beneath the shade roller shafts.

It is significant that my invention provides a new principle of construction for shade stops in that a stop means of some suitable character is mounted proximate the shade S and is carried between the arms 12 and 13, or 23, 32, or 40 so that the shade stick may come in contact with the stop means. In this way, the contact or stopping engagement and resulting strain is applied remotely from the shade edges so as to throw the strain on the shade portions other than at the edges. While the double stop rod construction

18—19, and the single stop rod construction 30, are shown by way of example to explain my invention, other forms of double or single stop rods may be employed without departing from the principles of my invention.

It is also apparent that ordinarily a shade stop is suspended from the shade S and is therefore beneath the shade, but it may be mounted in other positions depending upon 10 the position of the shade and the manner in which it is installed in the window when one comes to place or install one of these shade stops in service position.

The arms may be punched with round 15 apertures 14 and 15 as in the first form of the invention, or with square or rectangular shaped apertures 33 or shaft openings as in the third form of the invention. In the latter case, the square shaft, which is ordinarily 20 found on one end of a shade roller, is locked against turning by reason of the bracket B. Therefore if I use a square shaft hole 33 in any form of the invention, it follows that the rods 18—19 or 30 are also correspondingly 25 locked against rotation, and the device cannot be displaced from its most efficient operative position. Thus it is an advantage to use a square shaft hole 33 at one end of the shade stop, and in one bracket at least, so as to engage the square shaft of the shade 30 roller.

What I claim is:

1. A shade roller fixture comprising, support means carried proximate each end of a shade roller, a pair of parallel rods the ends of which are carried by the support means, and said rods being spaced apart to permit the shade to travel therebetween and against which a shade stick comes to rest.

2. A shade roller fixture comprising, an arm provided with an aperture adapted to be carried on the shaft at each end of a shade roller and supported freely therefrom, and means carried by and between the arms and held proximate the shade roller and between which the shade travels and against which a shade stick comes to rest.

3. A shade roller fixture comprising, an arm provided with an aperture adapted to be placed on the shaft at each end of a shade roller and depending freely therefrom, a pair of rods the ends of which are anchored in the arms, and said rods being arranged parallel and being spaced apart between which the shade travels and against which a shade stick comes to rest.

4. A shade roller fixture comprising an arm provided with an aperture adapted to be placed on the shaft at each end of a shade roller and depending freely therefrom, a shade stop carried by the arms hanging freely underneath the shade, said shade stop comprising means between which the shade travels, and said means being spaced apart suffi-

ciently to admit the thin edge of a shade stick 65 which is ordinarily tapered in cross section and to stop the thick edge of said shade stick thereagainst.

5. A shade roller fixture comprising, a pair of arms each of which are provided at one 70 end thereof with an aperture adapted to be placed on the shaft of a shade roller at each end thereof, a pair of parallel shade stick stop rods having their ends fixed to the lower ends of the arms, and said rods being spaced 75 apart to permit the shade to travel therebetween and to act as a stop against which a shade stick comes to rest.

6. A shade roller fixture comprising, a pair of arms each of which are provided at one 80 end thereof with an aperture adapted to be mounted on the shaft of a shade roller at each end thereof, a pair of parallel shade stick stop rods having their ends fixed to the arms, and means included in the structure of 85 the pair of rods to increase or decrease their length according to the width of a window and shade, and said rods being spaced apart to permit the shade to travel therebetween and to act as a stop against which a shade 90 stick comes to rest.

7. A shade roller fixture comprising, a pair of arms each of which are provided with an aperture adapted to be placed on the shaft of a shade roller at each end thereof, a pair 95 of parallel shade stick rods having their ends fixed to the arms, and each of said rods comprising a pair of telescoping members slidable one in the other by which the fixture is adjusted to accommodate any width shade 100 and window.

8. A shade roller fixture comprising, a pair of arms each of which are provided with a bearing aperture adapted to be placed on the shaft of a shade roller at each end thereof, 105 a pair of parallel shade stick stop tubes having their ends fixed to the arms, and each of said tubes comprising a pair of telescoping members slidable one in the other by which the fixture is adjusted to accommodate any 110 width shade and window.

9. A shade roller fixture comprising a pair of support arms each of which are provided with a bearing aperture adapted to be placed on a shade roller shaft, a pair of spaced parallel tubes anchored to each support arm; and the pair of tubes on one arm being slightly larger than the pair of tubes on the other arm, whereby the two pairs of tubes are telescoped together to complete the fixture.

10. A shade roller fixture comprising, a pair of support arms each of which are provided with a bearing aperture adapted to be placed on a shade roller shaft, a pair of spaced parallel tubes anchored to each support arm; and a small and large spaced parallel tube anchored to each arm, whereby said small and large tube on one arm are tele-

scoped onto the small and large tube on the other arm by which the space between the tubes is made uniform throughout.

11. A shade roller fixture comprising a pair of shade roller brackets having apertures therein to receive a shaft at each end of a shade roller, and having nail or screw holes therein to anchor the bracket to a window casing, and a pair of spaced parallel rods the 16 ends of which are carried by the brackets and between which rods a shade travels and against which rods a shade stick comes to rest.

12. A shade roller fixture comprising, support means carried concentric to the shaft at 15 each end of a shade roller, and a shade stop device carried on the end of the support means and extending throughout the width of the shade and against which a shade stick is stopped, and said device being adapted to be held proximate the shade roller and so formed 20 as to leave the shade and roller exposed to view.

13. A shade roller fixture comprising, an arm adapted to be suspended from a point 25 proximate each end of a shade roller, a shade stop carried with the lower end of each arm and against which a shade stick is stopped and extending throughout the width of the shade and means to lock at least one arm against rotation relatively to the roller.

14. A shade roller fixture comprising, an arm adapted to be suspended from a point proximate each end of a shade roller and concentric with the roller, a shade stop carried with the lower end of each arm and against which a shade stick is stopped and extending throughout the width of the shade, and means to lock the arm against rotation relatively to the roller.

15. A shade roller fixture comprising, a pair of arms each of which is made with an aperture by which the arms are suspended from a shade roller shaft, means cooperating with the shaft and apertures by which one or 45 both arms are locked against rotation on the shaft, and means carried by the pair of arms and extending throughout the width of the shade and against which a shade stick is stopped.

16. A shade roller fixture comprising, a

pair of arms each of which is made with an aperture by which the arms are suspended from a shade roller shaft, at least one arm being provided with an aperture including straight sides and corners and thus made 55 square to fit the square shaft on one end of a shade roller, and means carried by the pair of arms against which a shade stick is stopped.

17. A shade roller fixture comprising, a pair of arms provided with square apertures 60 to receive the shafts of a shade roller and thus be locked against rotation, and means carried by the arms against which a shade stick is stopped.

18. A shade roller fixture comprising, a 65 pair of arms provided with square apertures to receive the shafts of a shade roller and thus be locked against rotation, and a shade guide and stop member having each end anchored in the lower ends of the arms, and 70 said member reaching from one arm to the other and including spaced means between which a shade travels and against which a shade stick is stopped and engaged throughout the full length of the stick.

19. A shade roller fixture, adapted to be mounted on the shafts at the ends of a shade roller, comprising an arm provided with a bearing aperture, a slot extending through the arm to the bearing aperture by which the 80 shaft of a shade roller is introduced into the bearing aperture, and a shade stop carried on the lower end of the arm and extending and engaging throughout the width of the shade and length of a shade stick.

20. A shade roller fixture comprising, a pair of tubes telescoped one in the other and slidably adjustable to vary the length of the fixture, and each tube end being flattened and bent at right angles to provide two spaced 90 parallel arms, each of said arms being provided with a bearing aperture to receive a shade roller shaft, and said telescoped tubes being provided with a slot extending lengthwise from arm to arm and within which a 95 shade is guided.

In testimony whereof I affix my signature.

HERMAN L. STRONGSON.
